UNITED STATES PATENT OFFICE.

PERRY A. BRICK, OF GALION, OHIO, ASSIGNOR TO THE NATIONAL GRAVE VAULT CO.,
OF GALION, OHIO, A CORPORATION OF OHIO.

POWER-ELEVATED DUMPING TRUCK.

Application filed March 4, 1926. Serial No. 92,370.

This invention relates to dumping wagons or trucks and particularly to the means for pivotally supporting the body upon the chassis of the truck, and the means whereby the forward end of the body may be lifted by hand power to discharge the contents thereof or lowered into a horizontal position.

One of the objects of the invention is to provide means for pivotally supporting the body upon the chassis of the truck, such means being so constructed that the fulcrum upon which the body rocks will shift rearward as the body is tilted thus permitting the rear end of the body to be disposed farther from the ground than would otherwise be the case, and allowing the hinge point or fulcrum to be located only a short distance back of the center of the body so that the body is thereby nearly balanced and can be dumped by high speed gearing and a crank.

A further object is to provide a gear sector for the purpose of raising the forward end of the body provided with angularly bent lifting arms in a horizontal position extending forward and then downward and connected by links to the front end of the body thus permitting the hoisting mechanism to be set relatively close to the front end of the body and permitting the arms and links to be provided of proper length to lift the box to a desired angle without extending the lifting arms so far from the gear sector as would be necessary with straight lifting arms.

A further object in this connection is to provide lifting arms and links so arranged that a change of leverage is produced as the body is tilted which makes the load on the hoisting mechanism more nearly uniform at all times. More particularly the object is to secure increased leverage when the body is started upward from a horizontal position and when the load is greatest and reduce this leverage as the body is lifted.

Other objects will appear in the course of the following description.

My invention is illustrated in the accompanying drawings wherein:

Figure 1 is a side elevation of a dumping truck constructed in accordance with my invention;

Figure 2 is a top plan view of the supporting structure for the body;

Figure 3 is a section on the line 3-3 of Figure 1;

Figure 4 is a side elevation of a portion of the truck with the body tilted;

Figure 5 is a side elevation of one of the rockers and its support when the body is in a horizontal position;

Figure 6 is a like view to Figure 5 but showing the rocker tilted;

Figure 7 is a section on the line 7-7 of Figure 1.

Referring to these drawings it will be seen that I have illustrated the chassis A of an ordinary truck and having longitudinally extending beams *a* and that I have illustrated

an ordinary body designated B. This body is shown as having its bottom *b* provided with longitudinally extending angle or channel irons 10 disposed on each side of the body

and extending from the front to any desired point, and with a transverse angle or channel iron 11, slightly forward of the center of the body, and a transverse angle or channel iron 14, slightly to the rear of the center of the body. Disposed between the irons 11

and 14 are two pairs of longitudinally extending irons 15, provided with a plurality of transversely extending holes 16. The outside members of irons 15 may also be replaced by a continuation of longitudinal irons 10. A short channel iron (or two angle irons) 12 is disposed at the front end of the body and provided with a plurality of openings 13. Disposed upon the beams *a*

and held thereto by any suitable manner, as by bolts or clamps of any suitable character, is the approximately U-shaped member 17

which rests flat upon the beams *a* and is held thereto by the clamps 18, this U-shaped frame having an extreme width greater

than the distance between the exterior faces of the beams *a* so as to rest upon the upper edge faces thereof. Extending longitudinally from the U-shaped angle iron 17 are the parallel angle irons 19 which are bolted

to the base flange of the angle iron 17 and connected to a transverse iron 20 which rests upon the upper faces of the beams *a*. Engaged with the ends of this transverse iron

20 are the supporting irons 21 which are angularly bent at their upper ends and upon which the body B rests when the body is turned into a horizontal position.

Disposed inward and parallel to the rear ends of the U-shaped angle iron 17 are the

parallel angle irons 22 which are bolted to the base flange of the angle iron 17 and connected to a transverse iron 23 which rests upon the upper faces of the beams *a*. Engaged with the ends of this transverse iron

23 are the supporting irons 24 which are angularly bent at their upper ends and upon which the body B rests when the body is turned into a horizontal position.

Disposed inward and parallel to the rear ends of the U-shaped angle iron 17 are the

parallel angle irons 25 which are bolted to the base flange of the angle iron 17 and connected to a transverse iron 26 which rests upon the upper faces of the beams *a*. Engaged with the ends of this transverse iron

26 are the supporting irons 27 which are angularly bent at their upper ends and upon which the body B rests when the body is turned into a horizontal position.

longitudinally extending irons 22, riveted, bolted or otherwise attached to the angle iron 17 and extending across the space between the rear ends of the angle iron 17 and the irons 22 are the bolts or pins 23 and 23^a.

Disposed between the angle irons 15 of each pair of angle irons is an approximately segmental casting shown in detail in Figure 6, and designated 24, and constituting a rocker or fulcrum for supporting the body B. This casting has a plurality of transverse apertures 25 for bolts 26 which pass through certain of the bolt holes 16, and is also formed with an arcuate flange 27 projecting laterally on each side of the medially disposed web 28 of the casing, as shown in Figure 7. The rocker below the casting is formed with a plurality, as for instance three, sockets 29, 30 and 31. The semicylindrical socket 29 or recess is disposed a greater distance from the top of the casting than is the socket 30 and this in turn is disposed a greater distance from the top of the casting than the socket 31 so that as the body is tilted these three sockets will successively engage the three bolts or pins 23 and 23^a. This, of course, is equivalent to moving the hinge point rearward as the dumping operation progresses thus keeping the rear end of the dumping body farther from the ground than would otherwise be the case and allowing the hinge point to be located only a very short distance rearward of the center of the body. Thus the body is nearly balanced in its horizontal position and can be readily dumped with relatively small power.

The middle socket 30 of the rocker casting is formed to provide an elongated loop 32, the rear side wall of which is slightly offset as at 32^a, see Figure 6, and this loop 32 encloses the corresponding bolt or pin 23^a. When in a horizontal position this offset portion 32^a engages the lower face of the pin 23^a and thus acts to limit or prevent any upward movement of the body. When, however, the body is tilted and the rockers are rocked to turn the body from a horizontal position to a tilted position this loop 32 acts as an emergency stop limiting the tilting movement if for any reason the body should have a tendency to go past its predetermined dumping angle. This, of course, is secured by the lower end of the loop 32 coming in contact with the pin 23^a. Obviously when the body is in its horizontal position or in a tilted position the engagement of any one of the sockets 29, 30 or 31 with the corresponding pins or bolts 23 or 23^a prevents any longitudinal movement of the body with relation to the supporting frame. The rockers are supported upon the parallel irons through which the bolts 23 pass, by the flanges 27 so that the pins or bolts 23 do not have to support the load.

The hoisting mechanism comprises the transversely extending shaft 33 provided at one end with the crank handle 34 by which the shaft may be manipulated. This shaft carries upon it the pinion 35 and the shaft 70 is mounted in bearings in the front ends of the angle irons 19. The pinion 35 meshes with a gear wheel 36 mounted upon a shaft disposed in bearings extending through the angle irons 19 and this shaft carries upon it the pinion 37. Mounted in upstanding ears 38 is the shaft of a segment gear 39 which meshes with the pinion 37. This segment gear is provided with the radially extending short arm section 40 having sockets 75 on each side. Disposed in these sockets are the arm sections 41 which at their lower ends rest in the sockets and are bolted, riveted or otherwise connected thereto and at their outer ends are angularly bent as at 43 and extend nearly at right angles to the body of the arm. Pivottally engaged with the angular end 43 of arm 41 are the links 44 which are disposed on each side of the arm 43 and extend upward on each side of the channel iron 12 and are bolted thereto by the bolt 45 which may be disposed in either of the openings 13 as desired. The arm 41 is preferably formed of two thicknesses of material riveted to each other but angularly bent at the extremities of the arms as at 46 so as to hold the links suitably separated at their lower ends and to clear the drive shaft of truck chassis.

The shaft 33 carries upon it the ratchet 100 47 which is disposed adjacent the crank 34 and coacting with this ratchet is the double pawl 48. This pawl 48 is pivoted at 49, has a weighted handle 50 and the oppositely disposed teeth 51 which are adapted to engage between the teeth of the ratchet wheel 47 and hold the shaft from rotation in either direction. By shifting the pawl from a downwardly and outwardly inclined position in one direction to a downwardly and outwardly inclined position in the reverse direction the pawl is adapted to prevent rotation of the ratchet wheel in one or the other direction.

It will be seen that the angularity of the arm 41 is of great importance in that by angularly bending this arm so that the extremity of the arm extends downward when the body of the arm is in a horizontal position much longer links may be used and this permits the use of a shorter lifting arm 41 than would otherwise be required, and reduces the work to be done by the hoisting mechanism. Furthermore this construction of the lifting arm secures a change of leverage which makes more nearly uniform the load on the hoist as the elevation of the body progresses. This load is greatest at the start and at this time the active length of the lifting arm 41 is only from x to y , (see 115 120 125 130

Figure 1). As the body is elevated, however, the active lever length is increased until it is equal to the actual length x to z , (see Figure 4). This gives the hoisting mechanism a much greater leverage at the start when the load is greatest.

It will be noted that with this construction the rockers may be adjusted toward or from the forward ends of the body and thus 10 cause the body to be shifted forward or rearward relative to the chassis and furthermore that it is an easy matter to remove the rockers in case of breakage and substitute other rockers in place thereof.

15 The transversely extending bolts 23 and 23^a are preferably surrounded by spacing sleeves 51. The lifting unit may be readily removed from the U-shaped member 17 in case of necessity or applied thereto and the 20 lifting mechanism as a whole, including the supporting member 17, may be readily applied to a truck chassis.

While I have illustrated certain details of construction and arrangement of parts 25 which I have found to be particularly effective in actual practice, I do not wish to be limited thereto as it is obvious that many changes might be made therein within the scope of the appended claims.

I claim:—

1. A dumping truck including a chassis and a body, oppositely disposed rockers mounted on the body, each having an arcuate series of recesses in its under face, and the chassis having a series of members with which said recesses coact and mesh, one of said recesses being approximately elliptical, through which the corresponding member passes to thereby limit the tilting movement of the body and rockers upon the chassis. 30

2. A dumping truck including a chassis and a body, oppositely disposed rockers mounted on the body, each having an arcuate series of recesses in its under face, and the chassis having a series of members with which said recesses coact and mesh, one of said recesses being approximately elliptical, through which the corresponding member passes to thereby limit the tilting movement of the body and rockers upon the chassis, 40 the elliptical opening of each recess being forwardly offset to provide a rounded shoulder adapted to bear against the corresponding member when the body is in a horizontal position to thereby limit upward movement of the body relative to the chassis. 45

In testimony whereof I affix my signature.
